PUMPING ASSEMBLY

Roy A. Smith, Oklahoma City, Okla.

Application October 3, 1949, Serial No. 119,272

4 Claims. (CL. 255—28)

1

This invention relates to improvements in assemblies employed in deep wells for actuating pumps, bailers, and the like.

Ordinarily, pump rods, known as sucker rods, are used in deep wells in actuating pumping mechanisms. These sucker rods are about 30 ft. long and are provided with threaded ends capable of attachment to couplings which hold the entire string of sucker rods in position within the tubing of a well. Since tubing is ordinarily of relatively small diameter, these sucker rods, of necessity, have to be of small diameter. The sucker rods have to be handled very carefully during shipment and installation so as to prevent bending or distortion. The lowering and raising of sucker rods is a long, time-consuming and tedious process.

Workers in the field have recognized that wire cable has numerous advantages over sucker rods, and some attempts have been made to employ one long length of cable instead of the multitude of sucker rods. However, the disadvantages incident to the use of a long length of cable have been deemed insurmountable, since among these disadvantages is the fact that all forms of wire cable have a tendency to untwist in use, making it practically impossible to use a single long length of cable in a deep well. Moreover, no adequate or satisfactory method of wiping the cable at the top of the well and of completely sealing off whatever gas pressure might exist around the cable has been evolved.

The present invention is directed to an assembly which can be effectively used in actuating deep well pumps, bailers, etc., in an economical manner and without the necessity of employing a multitude of sucker rods as heretofore. Generally stated, the assembly contemplated by this invention may be said to comprise a polish rod extending through a normal well head assembly, wipers, oil savers, glands, etc., the lower end of said polish rod being connected to a plurality of consecutive sections of wire cable, said sections being composed of right-hand lay cable and left-hand lay cable sections alternately. These sections are connected by couplings, each coupling including a threaded connector adapted to receive a threaded end of a normal sucker rod. The lowermost section of such cable may therefore be readily connected to a sucker rod extending into the pump or other deep well mechanism which is to be actuated. Whenever desired, a section of sucker rod may be connected into the series of cable sections.

Such an assembly has many advantages. Since

5 the sections of cable are alternately composed of right-hand and left-hand lays, torque which may be developed in the assembly during pumping is counter-balanced and virtually eliminated so that there is no unravelling or untwisting to appreciably change the total length of the assembly. Furthermore, instead of employing the relatively short 30 ft. length of sucker rod, it is now possible to employ lengths of cable sections which are 60 ft., 80 ft., or 90 ft. in length, thereby eliminating from 50% to as high as 80% of the couplings normally employed in a working rod assembly. In practice, each section of wire cable is between about two and four times the length of a normal sucker rod. In addition, since the cable is flexible, these sections of cable may be hung in a derrick and need not be handled, during transportation, shipment, and installation, with the care that normal sucker rods require.

20 Furthermore, the invention contemplates the use of couplings carried by each end of a cable section, such couplings being provided with a threaded connector adapted to receive the end of a normal sucker rod. In this manner, cable sections are capable of connection with sucker rods or polish rods and the couplings or connectors themselves may be used interchangeably with either cable sections or sucker rods. In 25 other words, the usual sucker rod connector or pony rod may be used either in connecting sucker rods or sections of cable contemplated by this invention. There are many other advantages to the assembly herein contemplated, among them being the fact that while it is almost impossible to predetermine a latent weakness in a sucker rod, the impending failure of a length of cable is 30 visibly and readily indicated by examination, since such impending failure is, in most instances, evidenced by breakage of one or more individual strands composing the cable. As a result, the use of the present assembly prevents shut-downs 35 due to fatigue and breakage of sucker rods. It may also be noted that the present assembly is 40 not subject to failure due to its use in a crooked hole, whereas sucker rods cannot be successfully used for any protracted length of time in a 45 crooked hole.

45 It is an object of the present invention, therefore, to disclose and provide a novel deep well pump-actuating assembly employing alternate sections of right-hand and left-hand cable coupled together, in combination with a normal pony rod or sucker rod.

50 Another object of the invention is to disclose

and provide an assembly comprising sections of wire cable provided with couplings including threaded connectors adapted for engagement with normal sucker rods.

A still further object of the invention is to disclose and provide as an article of commerce a length of wire cable for use in actuating deep well pumps and the like, each end of said length of cable being firmly anchored in a coupling having a threaded end portion.

These and other objects, uses and advantages of the invention will become apparent to those skilled in the art from the following description of exemplary forms in which the invention may be embodied.

In the drawings:

Fig. 1 is a side elevation, partly diagrammatic, showing a typical assembly.

Fig. 2 is an enlarged side elevation, partly in section, through a coupling and connector between two consecutive cable sections.

Fig. 3 is an enlarged side elevation, partly in section, through a modified form of coupling.

Fig. 1 diagrammatically illustrates a conventional type of installation, it being understood that the precise type of casing head and the precise type and number of pipe strings may vary according to the particular characteristics of the individual well and the practice of individual drilling operators. The arrangement shown in Fig. 1 shows a casing head 16 connected to the upper end of surface casing or conductor pipe 11, a water string 12, casing 13, tubing 14. Extending downwardly through the tubing 14 to a pump 15 is the improved sucker rod assembly of this invention, generally indicated by the numeral 15. Such assembly may comprise the upper polish rod 17, alternate sections of right-hand and left-hand lay cable, such as 18, 19, 18', 19', etc., and a section of sucker rod 20 connected to the pump rod and plunger (not shown) in the pump barrel. Details of construction of the pump are not indicated, since they are not a part of the present invention and the structure and operation are well understood in the art.

The upper end of the polish rod may be connected through any suitable fitting with a walking beam or other pumping mechanism for reciprocating the assembly.

By referring to Fig. 2 (which illustrates a connection between two adjacent sections of cable), it will be noted that the lower end of the right-hand lay cable 18 is connected to the upper end of the left-hand lay cable section 19 by means of a coupling and connector. Since each end of a section of cable is similarly anchored in a coupling, the coupling carried by the lower end of cable section 18 is illustrative of all of the couplings.

The coupling carried by the lower end of cable section 18 (as shown in Fig. 2) comprises a cylindrical member 21 provided with an axially disposed port 22 leading to a recess 23 of enlarged section past outwardly flaring, inner wall surfaces 24. The enlarged recess 23 is arranged to receive the splayed end of cable 18 and such splayed end is then firmly held in place within the recess by means of Babbitt metal or other means. The body portion 21 may carry on its outer surface a collar of wear-resisting material 26, such collar being preferably spaced from a wrench flat 27, also formed in the outer surface of the coupling 21.

That end of the coupling 21 opposite the port or channel 22 is internally threaded, as indicated

at 28, with standard or normal sucker rod threads. It will be understood, therefore, that the cable section 18 can be readily connected to a standard sucker rod. It may also be connected to the standard or usual pony rods, such as the pony rod 30. A pony rod is a miniature, short length of sucker rod, each end thereof being provided with an outwardly extending threaded pin. The pony rod 30 can therefore be readily connected to the upper end of cable section 19 provided with the coupling 21', whereas the upper end of the pony rod can be readily connected to the coupling 21 carried by cable section 18.

Fig. 2 is therefore illustrative of a joint between successive sections of cable. Those skilled in the art will readily appreciate that any cable section can be connected to a sucker rod or to a polish rod. As a result, the assembly is an extremely flexible one in that the operator may use as many cable sections as he desires (preferably employing right-hand lay and left-hand lay sections alternately and in equal number within the assembly) or he may introduce polish rods, sucker rods, or the like, at any desired point. When, for example, the assembly is to be used in a deep well, the lower portions of which are filled with a corrosive oil or liquid, it may be well to use sucker rods in such lower section and cable sections thereabove, since sucker rods are more resistant to the action of corrosive liquids than ordinary unclad cable.

The modified form of coupling illustrated in Fig. 3 shows the end of right-hand lay cable section 18' extending into a recessed coupling member 31 and babbittted therein. This coupled section is provided with an internally threaded bore 32 adapted to receive a sub 33 provided with an externally threaded pin end 34 extending into a portion 35 which is internally threaded, the operating threads at 34 being identical to those employed on normal sucker rods. The sub member 35 is provided with an outwardly extending pin capable of engagement with the internal threads 32' on coupling body 31 in which the upper end of the left-hand lay cable section 19' is anchored. It will be noted, therefore, that an assembly composed of coupling 31 and sub body 35 may be either connected to an adjacent length of cable by means of the adapter 33 or to a normal sucker rod.

Attention is called to the fact that not only does the present assembly give rise to many economies, but it greatly facilitates and expedites the making up of a string. When couplings of the character shown in Fig. 2 are employed, substantially all of the parts used are standard and readily available. Moreover, the couplings are easily replaced when worn. The pins and boxes of the coupling members can be reclaimed and reused, even when a section of wire line is damaged or worn, by disconnecting the coupling member or box from the worn line and replacing it with new line. Such reclaiming and reuse is impossible with regular sucker rods. Furthermore, instead of discarding a complete drilling line, only that section which has kinked, worn or has been damaged need be discarded, and a new section can be readily inserted, thereby resulting in a definite saving to the operator. Those skilled in the art will appreciate the many advantages which flow from the construction hereinabove described.

All changes coming within the scope of the appended claims are embraced thereby.

I claim:

1. A deep well pump-actuating assembly comprising: a polish rod extending through a normal well head assembly, the lower end of said polish rod being connected to a plurality of consecutive sections of wire cable, said sections being composed of right-hand lay cable and left-hand lay cable sections alternately, said sections being connected by couplings, each including a threaded connector adapted to receive the threaded end of a normal sucker rod; and a sucker rod connected to said actuating assembly.

2. An assembly of the character stated in claim 1 wherein each section of wire cable is between about two and four times the length of a normal sucker rod.

3. A deep well pump-actuating assembly comprising: a polish rod extending through a normal well head assembly, the lower end of said polish rod being connected to a plurality of consecutive sections of wire cable, said sections being composed of right-hand lay cable and left-hand lay cable sections alternately, each end of each of said sections of wire cable being splayed and firmly anchored in a coupling provided with an axially disposed recess having outwardly flaring inner wall surfaces and arranged to receive the splayed end of the cable, and also provided

5 with an internally threaded end portion and a wrench flat formed in the outer surface of the coupling; said consecutive sections of wire cable being connected by subs engaging opposite, threaded end portions of the couplings; and a sucker rod connected to said actuating assembly.

4. A deep well pump-actuating assembly of the character stated in claim 3, wherein a collar of wear-resisting material is carried by the outer

10 surface of each of the couplings, whereby the assembly may be effectively used in deep and crooked well holes.

ROY A. SMITH.
